A CORPORATION OF DELAWARE.

MACHINE-GUN.

1,256,923.

Specification of Letters Patent. Patented Feb. 19, 1918.

Application filed August 16, 1916. Serial No. 115,127.

To all whom it may concern:

Be it known that I, CHARLES A. NELSON, a citizen of the United States, and a resident of Utica, Oneida county, State of New York, 5 have invented certain new and useful Improvements in Machine-Guns, of which the following is a full, true, and complete specification.

This invention is an improvement in gas 10 operated machine or similar automatic guns and relates more particularly to the agents whereby the gas pressure of the explosion is utilized for the operation of the loading mechanism. Merely as an example of a gun 15 having such agents I refer to the well-known Savage-Lewis machine gun in which there is employed a gas-impelled rod or plunger mechanism formed of two sections connected together in alinement, one constituting a piston rod and piston subject to the gas pressure escaping laterally from the barrel, and the other section being a motion-transmitting and motion-distributing member serving to actuate the several parts 20 of the loading and other mechanism. As said member moves under the pressure of the gas imparted to it through the piston rod, it acts through a cam-slot, or otherwise, to rotate the breech bolt and unlock it 25 and to carry it rearwardly against spring pressure until the empty shell is ejected, and immediately following ejection, the spring pressure returns the said member, and during the return movement a new cartridge is 30 placed in the chamber of the barrel, the breech bolt being automatically restored and locked in its restored position and the firing pin being cocked or cocked and immediately released, according to whether the trigger 35 is held pulled during the gas operation. Other parts are likewise actuated by and during the reciprocation of the said section. But, although I have made my invention primarily as an improvement on the said 40 Savage-Lewis gun, it is also applicable for use in connection with any other type of gun or apparatus where the same, or similar parts, or a similar cycle is performed, and the features characterizing my invention 45 are, therefore, broadly claimed below.

The immediate object of the invention is to avoid or prevent fracture of the reciprocating plunger mechanism in the vicinity of the joint or junction between the piston rod 50 proper and the part or section actuated by

it. These parts for certain reasons are required to be disconnectable, and in the gun referred to, as well as in others operating on the same principle, a condition of stress localizes at the region of the attachment and 55 fracture of the piston rod, due to crystallization of the metal, has heretofore frequently resulted attended, of course, with disassembly of the gun. Reinforcement of the joint in the region of fracture, as by the 60 use of thicker cross-sections, is not a remedy and is moreover forbidden in any substantial degree by the condition that these guns must be as light as possible so as to be capable of use as a shoulder arm.

I have discovered that I can eliminate the cause of breakage, without thicker metal, by connecting the two sections with a loose joint and a spring for controlling the joint, by which means I retain the sections in 70 proper relative positions, prevent any material endwise movement and prevent localization of the injurious stresses in either of the sections and especially at the place where fracture is most likely to occur. In its improved and preferred construction as herein shown, the loose joint permits a certain relative rotary movement between sections while the spring controlling member, preferably a 75 helical spring, tends to prevent and restrain such movement, and the arrangement is such that disconnection of the sections can be accomplished very readily and without the use of tools.

In the accompanying drawings I have illustrated one form of my invention incorporated in the Savage-Lewis machine gun above alluded to.

Figure 1 is a central longitudinal section of this gun, certain portions not relating to the invention being omitted.

Fig. 2 is a view on a larger scale and similar to a portion of Fig. 1,

Fig. 3 is a transverse section on the line III—III of Fig. 1,

Fig. 4 is a section on the line IV—IV of Fig. 2,

Fig. 5 is an enlarged sectional detail showing the connection between the actuating plunger sections, and

Fig. 6 is a side elevation of the spring-yielding member employed in said connection.

In these drawings the gas-operated plunger mechanism comprises a piston rod sec-

tion 10 and a motion-transmitting section 11. The piston rod section 10 has a piston head 12 at its end and is mounted to slide in a cylinder 13 secured to the gun barrel 14 and 5 in communication therewith through a vent 15 forward of the piston head. The motion-transmitting section 11 is connected to the piston section by the loose joint and spring 0 presently described, and is mounted to slide partly within the cylinder 13 and partly in 5 a slideway formed in the receiver of the gun on which the barrel and many of the other parts of the gun are mounted. The breech bolt 16, mounted to slide and also to rotate in the receiver, and provided with the usual bayonet lugs for locking with the breech, is the principal member directly operated by the section 11. In its central chamber 17 it contains the striker or firing pin 18, and the latter is connected to the post 19 on the section 11, through a slot 20 in the wall of the bolt. This slot is curved or provided with cam surfaces 21 and 22 so that when the post approaches one end of the slot, it rotates the breech bolt in one direction and as it leaves this end of the slot reverses the rotation and thereby performs the function of locking and unlocking the bolt as will be understood. The sectional contour of the section 11 is designed to hold it to a non-rotary movement of reciprocation in the receiver whereby it may properly rotate the breech bolt as just described. On its lower side it is formed with a row of rack teeth 23 accommodated in a groove in the receiver and engaged with a spring-barrel gear-wheel 24. The spring acting on this gear tends to rotate it in the direction to restore the section 11 and the piston rod to their forward position. Each gas-impelled rearward motion of the piston takes place against the spring, and the adjusted tension of the latter controls the rapidity of fire which in practice is very rapid. The drawings show the sear and trigger combination and certain other parts which will be recognized without further description. These have no direct relation to my invention, which, as above stated, is concerned with the integrity of the junction between the piston rod and the rack member from which the breech bolt, firing pin and other parts receive their motion.

The joint between the piston and the rack member has heretofore been made by cross-screwing the former in a socket end in the latter and also by other forms of positive and more or less rigid connections intended to provide maximum security, though in practice ineffectual for that purpose. If the joint itself withstands the strain of rapid firing, the fracture tends to occur in the piston rod just in advance of the joint, and due in my opinion to the lack of accommodation in the latter.

In the new joint the socket in the end of the rack-member is retained and the piston rod is screw-threaded into it, preferably with square threads and rather loose, as intended to be shown at 25 in Fig. 5. The governing spring 26, separately shown in Fig. 6, is placed on the rod between a collar or shoulder 27 thereon and the end of the socket, with its out-turned ends 28 seated in notches 29 and 30, respectively in the 75 socket end and collar. This assemblage may be accomplished by holding one end of the spring out of its notch while the rod is being screwed into the socket and allowing it to seat in its notch when the rod is in place. 80 In the normal relation it is intended that the spring be free from distortion so that it will tend to resist relative rotation of the parts in either direction, and so that it will restore them to normal if momentarily 85 displaced. Preferably, the pitch of the threads is so related to the pitch of the coils of the spring that rotation of the piston rod in a direction to screw it out of the socket will contract the spring against the 90 rod and further rotation will be thereby prevented, while rotation in the opposite direction, will tend to squeeze the coils of the spring between the collar 27 and the end of the socket, which eventually forms a positive limit to such reverse rotation. Thus, the spring itself may constitute a stop for 95 limiting the relative rotation of the parts in either direction from normal, but other means may be provided for preventing accidental separation, where springs of different form or in different relation are used for governing the positions of the jointed parts. The helical form of spring is preferred for the gun in question because of its 100 simplicity and ease of assemblage with the screw-type of connection, and the said type of connection is preferred because it is readily disconnectible while providing maximum surface to withstand the thrust. Disconnection is accomplished by lifting one end of the spring and unscrewing the rod, no tools being required. It will be apparent however, that the sections can be connected in proper thrust-sustaining relation by other 110 means if desired, so long as their relative positions are subject to the control of the spring. My invention is thus not confined to the specific joint illustrated, although the features thereof constitute important adjuncts to the principle thereof. 115

I claim—

1. A gun having gas-operated plunger mechanism including a piston section, a motion-transmitting section, connections for preventing relative longitudinal movement of the sections, and a spring permitting but resisting relative rotary movement. 125

2. Plunger mechanism for automatic, gas-operated guns including a mechanism actu- 130

ating section, a reciprocating piston section, a detachable connection for longitudinally operating one by the other, and resilient means interposed between the said sections 5 adapted to resist relative rotary movement therebetween.

3. Plunger mechanism for automatic discharge-actuated guns, including a piston rod section, a mechanism-actuating section, a 10 connection therebetween whereby the one may impart longitudinal movement to the other, and spring means tending to prevent relative rotary movement between said sections.

15. 4. In apparatus of the kind described the combination of two reciprocating power-transmitting sections, subject to rapid end-wise vibration and connected to each other by screw-type engaging means and spring 20 means, yieldingly resisting relative rotary movement between said sections in either direction.

25. 5. In apparatus of the kind described, the combination of two reciprocating power-transmitting sections subject to rapid end-wise vibration and connected to each other by means permitting relative rotary movement therebetween, and spring-means resisting such movement and providing a positive limit thereto.

30. 6. In apparatus of the kind described, a rod section, a mechanism actuating section, a screw-threaded connection between said sections, and a coil spring restraining relative rotary movement of said sections.

35. 7. In guns of the kind described, a piston section, a mechanism actuating section, a

screw-threaded connection between said sections, and a coil spring tending to prevent relative rotary movement of said sections 40 and positively limiting the extent of such rotary movement in either direction.

8. An actuating rod including two sections having loose threaded connection with each other, and a coil spring encircling one 45 section, slightly larger than the portion encircled and having one end connected to each section.

9. An actuating means for automatic machine guns, including a piston section, a bolt 50 actuating section, and means for preventing the transmission of excessive stress to the piston rod section comprising a loose threaded connection between said sections and a coil spring loosely encircling one section and 55 having one end connected to each section.

10. A reciprocating plunger mechanism including two sections, one of said sections having one end threaded into one end of the other, and a coil spring encircling one 60 section of said sections adjacent to the other section and of slightly larger diameter than the portion encircled and having its opposite ends connected to the two sections, the pitch of the screw threads and of the spring 65 coils being such that a relative rotation of said sections in one direction is limited by the contraction of the spring against the part encircled, and relative rotation in the opposite direction is limited by the endwise 70 compression of the coils of the spring.

In testimony whereof, I have signed this specification.

CHARLES A. NELSON.
